STOP MOTION FOR FIBER STRAND
PREPARATION MACHINESFrederick Exley, Providence, R. I., assignor of
one-half to William Casey, Providence, R. I.

Application May 26, 1933, Serial No. 673,072

14 Claims. (Cl. 19—165)

My invention relates to improvements in electric stop motions for fiber strand preparation machines, specifically drawing frames having sets of draft rolls for the fiber strands, a source of fiber strand supply, mechanism to stop the motion of said draft rolls, electro-responsive means to release said stop motion mechanism and an electric circuit connected to said electro-responsive means and my invention specifically includes in said combination switch means connected to and normally breaking said circuit mounted on said machine underneath said fiber strands ahead of said draft rolls and having a roughened movable part adapted to be engaged by a broken strand of fiber and to be pulled thereby through the action of said draft rolls to complete the circuit to actuate said electro-responsive means to release said stop motion mechanism.

10. Hitherto in drawing frames and like devices substantially all the stop motion mechanisms of which I am aware have had as their actuator an element normally held up by the respective strands of roving or fiber and adapted to fall when a broken strand of roving should pass there- 15. through to actuate by its own weight either an electrical or a mechanical stop motion mechanism.

I am also aware of a device which permits the fiber to fall and by the action of its own weight 20. on an electrical member in an electric circuit to stop the machine. So far as I am aware, however, I am the first to provide an actuator for stop motion mechanisms for drawing frames, which when a broken strand exists will fall on a rough 25. and movable part of the switch or actuator and permit the strand to so engage the roughened part thereof that when the strand is tended to be pulled forward by the draft roll, it will pull said roughened parts of said switch to complete 30. a circuit which will actuate the electro-responsive means which will release the stop motion mechanism.

An object of my invention therefore, is to provide a novel combination in a drawing frame or 35. like machine working on this principle, and an approved specific type of electric switch or actuator for this purpose. The disadvantage of the former types is that the weighted parts tend to drag on the sliver or roving and tend to cause 40. irregularities therein, which irregularities generally include a roughened outside edge on the sliver or roving.

A further disadvantage is that if the roving 45. should happen to become loose the machine 50. would often stop without any actual broken ends.

While I am aware that a patent has been issued on the device hitherto described actuated by the weight of the sliver or roving falling thereon, so far as I am aware this device has not gone into general use, due to the fact that the weight of 5. the sliver or roving is too small of itself to actuate even a very flexible switch.

An object of my invention therefore, is to provide a type of an actuator which is highly sensitive and which will permit the change in position of the sliver due to a broken end to engage and drag on a freely tiltable or movable member to permit the action of the draft rolls themselves through the medium of the broken end of roving or fiber to pull the switch to complete the circuit 10. to actuate the stop motion mechanism. I therefore provide a positive type of stop motion mechanism which will function at all times to pull and actuate the lightly balanced switch. While my invention is primarily adapted for use in drawing 15. frames, it is obvious that it may be employed in any type of fiber strand preparation machine, namely, one used in the preparation of roving, sliver, slubbing, yarn, etc.

These and such other objects of my invention 20. as may hereinafter appear will be best understood from a description of the accompanying drawing which illustrates an embodiment there- 25. of.

In the drawing, Fig. 1 is a diagrammatic per- 30. spective view of a portion of a drawing frame showing one flier thereof in the act of twisting and drawing a single strand from a plurality of bobbins on a creel.

Fig. 2 is a front elevation of my improved ac- 35. tuator connected with a diagrammatic representation of a common type of electric stop motion mechanism for a drawing frame.

Fig. 3 is an end elevation of my improved switch or actuator with a strand of roving pass- 40. ing thereover and illustrating in dotted lines how the switch is tilted when a broken end falls there- 45. on by the action of the draft rolls.

In the drawing, wherein like characters of ref- 50. erence indicate like parts throughout, Fig. 1 dia- 55. grammatically illustrates a portion of a drawing frame on which my invention may be attached. While my invention may be employed in any type of a fiber strand preparation machine, I have illustrated it in connection with a drawing frame 50. 10. Said drawing frame 10 includes a usual lifter rail 12 reciprocatable in the usual manner on which the bobbins 14 are mounted and on which the fliers 16 are rotatably mounted. The rails 12 are adapted to wind the formed roving 18 on 55.

the bobbin 14. Said drawing frame includes the usual front draft rolls 20, carrier or intermediate draft rolls 22 and rear draft rolls 24. As I have shown my invention applied to a worsted drawing frame, it is obvious that the respective rolls consist of sets of upper and lower rolls between which the fiber strands or roving 18 are adapted to be passed. It is obvious that the draft is imparted to the roving between the back rolls 24 and the front rolls 20, the front rolls 20 being driven at a greater peripheral speed than the peripheral speed of the back rolls 24. In the embodiment shown, a worsted drawing frame, strands of roving 32 are drawn from the roving bobbins 26 over suitable guide bars 28 and placed in alignment over the main guide bar 30 in spaced relationship. The arrangement of bobbins is normally called a creel and is the source of roving or other fiber strand supply. The individual strands of roving 32 after passing over the main guide bar 30 are paired up in the slots 34 of the guide 36 mounted on said drawing frame so as to be just in front of the rear draft rolls 24. So much hitherto described are common features of drawing frames at present employed.

As diagrammatically illustrated in Fig. 2 the draft rolls 20 and 24 respectively may be driven through a common drive shaft 38 having thereon a fast pulley 40 and a loose pulley 42 and a belt shifter 44 is mounted on the drawing frame and includes a longitudinally slidable rod 46 having a belt fork 48 mounted on the end thereof and having a stop 50 on another portion thereon adapted to be contacted by one end of a shifting lever 52, the opposite end of which is pivotally mounted as at 54 on a portion of the drawing frame and is normally urged outwards to abut the stop 50 to move the rod 46 and fork 48 to shift the belt from the fast to the loose pulley by means of the spring 56 having one end attached to a portion thereof and the opposite end attached to a portion of the drawing frame. A trigger device 58 has a portion 60 thereof rigidly attached to the shifter lever 52 and a trigger finger 61 pivoted on the end thereof adapted to be retained by a projection 63 on a core 64 normally contained within a solenoid 66. The solenoid 66 is connected to an electric circuit 68 and is also grounded on the frame. When the electric circuit 68 is open, the finger will be normally retained behind the projection 63 to keep the belt on the fast pulley. When, however, the circuit is completed through an actuator or switch about to be described which forms the main feature of my invention, the core 64 will drop thereby releasing the finger 61 to permit the spring 56 to move the trigger 58, lever 52, shaft 46 and belt fork 48 outwardly to shift the belt from the fast to the loose pulley.

So much of the stop motion mechanism heretofore described also forms the standard parts of the electric stop motion mechanism on the market today and an improved switch type of actuator and the novel combination of this improved type of switch with the balance of the stop motion mechanism and parts of the drawing frame heretofore described forms my invention. As shown, I provide switch means connected to and normally breaking said circuit mounted on said machine underneath said fiber strands ahead of said draft rolls and having a roughened movable part adapted to be engaged by a broken strand of fiber and to be pulled thereby, by the action of said draft rolls to actuate said electro-responsive means, namely, solenoid, magnet, etc.

to close the circuit to release the stop motion mechanism in the well known manner described. In my preferred embodiment said switch means is preferably tilttable and placed in a position so that the roughened upper surface thereof will be engaged by the broken end and pulled thereby through the action of the draft rolls to move the tilttable switch member to a position to complete said circuit to actuate the stop motion mechanism. In my preferred embodiment said switch means includes the U-brackets 70 which are suitably mounted on a bracket 72 extending longitudinally of the drawing frame underneath the strands of roving just prior to their being led into the guide bar 36. The brackets 70 therefore, are mounted at desired spaced intervals on the supporting bracket or bar 72 and it is thus obvious that the brackets are grounded in a suitable manner, usually by their method of mounting. In my preferred embodiment, the bases, of the individual brackets are secured by means of screws 74 to the bar 72 and the end portions 76 of each bracket are provided with the transverse slits 78 to divide the end walls 76 of each bracket into lower and upper respective end wall portions 80 and 82 respectively. To secure the upper and lower end portions of the end walls and brackets securely together I preferably provide the insulation blocks 84 extending upwards the normal length of said end walls 76 and 30 secured by suitable means such as the screw means 86 to the upper end wall portion 82 and to the lower end wall portion 80. I also provide electric circuit connecting means projecting from one upper split wall portion, in the embodiment 35 shown comprising an arm 88 which is adapted to be electrically connected to the wall portion 82 by a bolt means 86 and by means of the bolt 90 to a bar 92 extending the length of the machine. Said bar 92 is thus connected to the 40 upper wall portions 82 of each respective bracket 70 on the bar 72. For the end bracket, a binding post 94 is electrically connected by means of the said screw means 86 to the upper end wall portion 82 that connects the arm 88 thereto and I 45 normally employ the end switch of the drawing frame for connecting the end of the electric circuit thereto, the respective arms 88 and electric connecting bar 92 being provided for connecting all the upper end portions 82 of the brackets together without individual wires. If desired, however, individual binding posts 94 may be provided for the top portions 82 of each respective bracket. It is obvious, however, that the arms 88 may be formed integral with the upper end wall portions 55 82 if desired. One upper end wall portion 82 of each bracket is provided with a bumper pin 96 and a lower end wall 80 is provided with a contact pin 98 vertically offset from said bumper pin 96 for a purpose to be described. The portions of 60 the switch heretofore described comprise the stationary parts of the switch to which the various electrical connections are made. On said bracket 70, I mount the tilttable arm 100, which in my preferred embodiment comprises a U-arm 100 65 having the upper portion 102 with the downwardly projecting arms 104 and 104^a having the pins 106 projecting inward therefrom adapted to rest in suitable holes 108 in the upper portions 82 of the end walls of said brackets. It is obvious that 70 the pins 106 are suitably mounted in holes 108 so as to permit free tilting of the arms 102 therein. If desired, however, instead of making the U-shaped bracket a tilttable arm I may construct these of a single end, in which case an end 104 75

pivotally mounted on the bracket end may be insured against longitudinal movement thereon in any suitable fashion. In the U-shaped bracket as shown due to the construction of the pins 106 projecting inwards it is obvious that the opposite end walls 104 and 104^a will prevent the pins 106 from sliding longitudinally out of their respective holes 108.

It is apparent that on breakage of a roving strand 32 the broken portion 33 thereof (see Figs. 1 and 3) will fall on the roughened upper surface 103 of said arm 100. While said upper surface 103 may be roughened in any suitable manner, as shown in my preferred embodiment I preferably secure a zinc strip 105 provided with the projections 107 suitably pierced therein to form the roughened upper surface 103 of said arm 100. It is thus obvious that the broken portion 33 will contact said zinc points 107 or roughened upper surface and become intermeshed therewith, so that the end 33 being pulled forward as usual by means of the rear draft rolls 24, will tilt the arm 100 from the position shown in full lines in Fig. 3 to the dotted line position shown therein, causing the lower end of the arm 104^a to contact the contact pin 98 to complete a circuit through the binding post connection 94, the upper end wall portion 82, the bus bar connection 92, through the pin 106 contacting the hole 108 in said upper end wall 82 and downwards through the arm 104^a thereof to contact the contact pin 98, which in turn is mounted on the lower end portion 80 and thus is grounded to the frame through the usual bracket base 70 and supporting bar 72 and thus completing a circuit through the electromagnet to cause the trigger 61 to move away from the projection 63 in the core thereof to permit the spring 56 to actuate the stop motion mechanism to shift the belt from the fast to the loose pulley. In my preferred embodiment the arm 104^a of the switch 100 preferably projects downwardly a greater distance than the other arm and then is bent rearwardly as at 109 to form a balance to pivot the movable arm 100 of said switch to a normal position contacting the bumper pin 96 and out of contact with the contact pin 98, said elongated end therefore functioning as a weight for this purpose to return the arm to a normal substantially vertical position when the broken end of roving 33 is removed therefrom.

It is apparent therefore that I have provided a novel type of stop motion mechanism and actuator therefore which operates in an entirely novel manner, namely, by the broken end falling on and engaging the roughened movable portion thereof and pulling it to actuate the switch through the medium of the forward motion of the draft rolls 24 and it is apparent that I have provided a very sensitive device which through the inherent longitudinal strength of the broken strands 33 is extremely positive in its action. If desired, as shown, the circuit may be provided with a transformer to reduce the normal current so low that it will have no harmful effect on the operator.

It is understood that my invention is not limited to the specific embodiment shown and that various deviations may be made therefrom without departing from the spirit and scope of the appended claims.

What I claim is:

1. In a drawing frame, a source of roving supply, driven draft rolls for said roving, mechanism to stop the motion thereof, electro-re-

sponsive means to release said stop motion mechanism, an electric circuit connected to said electro-responsive means and pivoted switch means connected to and normally breaking said circuit pivotally mounted on said machine underneath said roving ahead of said draft rolls having a rigid roughened upper surface portion adapted to be engaged by a broken strand of roving and to be pulled thereby through the action of said draft rolls to pivot said switch means through the pulling action of the roving alone to complete the circuit to actuate said electro-responsive means to release said stop motion mechanism.

2. In a fiber strand preparation machine, a source of fiber strand supply, driving draft means for said fiber strands, mechanism to stop the motion thereof, electro-responsive means to release said stop motion mechanism, an electric circuit connected to said electro-responsive means and pivoted switch means connected to and normally breaking said circuit pivotally mounted on said machine underneath said fiber strands having a rigid roughened upper surface portion adapted to be engaged by a broken strand of fiber and to be pulled thereby through the action of said driving means to pivot said switch means through the pulling action of the fiber strands alone to complete the circuit to actuate said electro-responsive means to release said stop motion mechanism.

3. In a drawing frame, a source of roving supply, driven draft rolls for said roving, mechanism to stop the motion thereof, electro-responsive means to release said stop motion mechanism, an electric circuit connected to said electro-responsive means, switch means connected to and normally breaking said circuit pivotally mounted on said machine underneath said roving ahead of said draft rolls having a rigid roughened movable surface portion adapted to be engaged by a broken strand of roving and to be pulled thereby through the action of said draft rolls to pivot said switch means through the pulling action of the roving alone to complete the circuit to actuate said electro-responsive means to release said stop motion mechanism.

4. In a fiber strand preparation machine, a source of fiber strand supply, driving means for said fiber strands, mechanism to stop the motion thereof, electro-responsive means to release said stop motion mechanism, an electric circuit connected to said electro-responsive means and switch means connected to and normally breaking said circuit pivotally mounted on said machine underneath said fiber strands having a rigid roughened movable surface portion adapted to be engaged by a broken strand of fiber and to be pulled thereby through the action of said driving means to pivot said switch means through the pulling action of the fiber strands alone to complete the circuit to actuate said electro-responsive means to release said stop motion mechanism.

5. An actuator for electric stop motion mechanisms for a fiber strand preparation machine having driven draft means, a source of fiber strand supply a stop motion mechanism and an electro-responsive stop motion release mounted and grounded on said machine comprising, a U-bracket adapted to be mounted and grounded on said machine underneath said fiber strands between said draft means and the source of fiber strand supply having transverse slits in the end walls thereof, insulation blocks adjacent the

- split portions of said end walls, means connecting said blocks to said upper and lower split wall portions, stop motion release electric circuit connecting means projecting from one upper split wall portion, a bumper pin on one end wall and a contact pin on a lower end wall portion vertically offset from said bumper pin and a U-arm having a roughened corrugated zinc plate mounted over the upper surface thereof and the end walls thereof pivotally mounted on said upper end wall portions of said U-bracket, whereby on breakage of a fiber strand, the broken portion moved by said draft means may fall on said corrugated surface and tilt said U-arm from a normal position contacting said bumper pin to a tilted position contacting said contact pin to complete the grounded circuit to actuate said electro-responsive stop motion release, one wall of said tiltable arm being extended to tilt said U-arm to a normal position against said bumper pin on release of said fiber strand.
6. An actuator for electric stop motion mechanisms for a fiber strand preparation machine having driven draft means, a source of fiber strand supply, a stop motion mechanism and an electro-responsive stop motion release mounted and grounded on said machine comprising a U-bracket adapted to be mounted and grounded on said machine underneath said fiber strands between said draft means and the source of fiber strand supply having transverse slits in the end walls thereof, insulation blocks adjacent the split portions of said end walls, means connecting said blocks to said upper and lower split wall portions, stop motion release electric circuit connecting means projecting from one upper split wall portion, a bumper pin on one end wall and a contact pin on a lower end wall portion vertically offset from said bumper pin, and a U-arm having a roughened surface and the end walls thereof pivotally mounted on said upper end wall portions of said U-bracket, whereby on breakage of a fiber strand the broken portion moved by said draft means may fall on said roughened surface and tilt said U-arm from a normal position contacting said bumper pin to a tilted position contacting said contact pin to complete the grounded circuit to actuate said electro-responsive stop motion release.
7. An actuator for electric stop motion mechanisms for a fiber strand preparation machine having driven draft means, a source of fiber strand supply, a stop motion mechanism and an electro-responsive stop motion release mounted and grounded on said machine, comprising a U-bracket adapted to be mounted and grounded on said machine underneath said fiber strands between said draft means and the source of fiber strand supply having transverse slits in the end walls thereof, insulation blocks adjacent the split portions of said end walls, means connecting said blocks to said upper and lower split wall portions, stop motion release electric circuit connecting means projecting from one upper split wall portion, a bumper pin on one end wall and a contact pin on a lower end wall portion vertically offset from said bumper pin and a U-arm having a roughened corrugated zinc plate mounted on the upper surface thereof and the end walls thereof pivotally mounted on said upper end wall portions of said U-bracket, whereby on breakage of a fiber strand the broken portion moved by said draft means may fall on said corrugated surface and tilt said arm from a normal position contacting said bumper pin to a tilted position to contact said contact pin to complete the grounded circuit to actuate said electro-responsive stop motion release, one wall of said tiltable arm being extended to tilt said arm to a normal position against said bumper pin on release of said fiber strand.
8. An actuator for electric stop motion mechanisms for a fiber strand preparation machine having driven draft means, a source of fiber strand supply, a stop motion mechanism and an electro-responsive stop motion release mounted and grounded on said machine comprising a U-bracket adapted to be mounted and grounded on said machine underneath said fiber strands between said draft means and the source of fiber strand supply having transverse slits in the end walls thereof, insulation blocks adjacent the split portions of said end walls, means connecting said blocks to said upper and lower split wall portions, stop motion release electric circuit connecting means projecting from one upper split wall portion, a bumper pin on one end wall and a contact pin on a lower end wall portion vertically offset from said bumper pin and a U-arm having a roughened surface and the end walls thereof pivotally mounted on said upper end wall portions of said U-bracket, whereby on breakage of a fiber strand the broken portion moved by said draft means may fall on said roughened surface and tilt said U-arm from a normal position contacting said bumper pin to a tilted position contacting said contact pin to complete the grounded circuit to actuate said electro-responsive stop motion release.
9. An actuator for electric stop motion mechanisms for fiber strand draft machines having driven draft means, a source of fiber strand supply, a stop motion mechanism and an electro-responsive stop motion release mounted and grounded on said machine comprising a bracket adapted to be mounted and grounded on said machine underneath said fiber strands between said draft means and source of fiber strand supply having a transverse slit in an end wall thereof, an insulation block adjacent the split portion of said end wall, means connecting said block to said upper and lower split wall portions, stop motion release electric circuit connecting means projecting from the upper split wall portion, a bumper pin on the end wall and a contact pin on the lower end wall portion vertically offset from said bumper pin and an arm having a corrugated zinc plate mounted on the upper surface thereof and the end wall thereof pivotally mounted on said upper end wall portion of said bracket, whereby on breakage of a fiber strand the broken portion moved by said draft means may fall on said corrugated surface and tilt said arm from a normal position contacting said bumper pin to a tilted position to contact said contact pin to complete the grounded circuit to actuate said electro-responsive stop motion release, one wall of said tiltable arm being extended to tilt said arm to a normal position against said bumper pin on release of said fiber strand.
10. An actuator for electric stop motion mechanisms for fiber strand draft machines having driven draft rolls, a source of roving supply, a stop motion mechanism, and an electro-responsive stop motion release mounted and grounded on said machine comprising a bracket adapted to be mounted and grounded on said machine underneath said fiber strands between said draft rolls and source of fiber strand supply having a transverse slit in an end wall thereof, an insula-

tion block adjacent the split portions of said end wall, means connecting said block to said upper and lower split wall portions, stop motion release electric circuit connecting means projecting from the upper split wall portion, a bumper pin on the end wall, and a contact pin on the lower end wall portion vertically offset from said bumper pin and an arm having a corrugated zinc plate mounted on the upper surface and the 10 end wall thereof pivotally mounted on said upper end wall portion of said bracket, whereby on breakage of a fiber strand, the broken portion moved by said draft rolls may fall on said corrugated surface and tilt said arm from a normal 15 position contacting said bumper pin to a tilted position to contact said contact pin to complete the grounded circuit to actuate said electro-responsive stop motion release, one wall of said tiltable arm being extended to tilt said arm 20 to a normal position against said bumper pin on release of said fiber strand.

11. An actuator for electric stop motion mechanisms for fiber strand draft machines having driven draft rolls, a source of roving supply, a 25 stop motion mechanism and an electro-responsive stop motion release mounted and grounded on said machine comprising a bracket adapted to be mounted and grounded on said machine underneath said fiber strands between said draft 30 rolls and source of fiber strand supply having transverse slits in an end wall thereof, an insulation block adjacent the split portions of said end wall, means connecting said block to said upper and lower split wall portions, stop motion 35 release electric circuit connecting means projecting from the upper split wall portion, a bumper pin on the end wall and a contact pin on the lower end wall portion vertically offset from said bumper pin and an arm having a corrugated 40 upper surface and the end wall thereof pivotally mounted on said upper end wall portion of said bracket, whereby on breakage of a fiber strand, the broken portion moved by said draft rolls may fall on said corrugated surface and tilt said arm 45 from a normal position contacting said bumper pin to a tilted position to contact said contact pin to complete the grounded circuit to actuate said electro-responsive stop motion release, one wall of said tiltable arm being extended to tilt 50 said arm to a normal position against said bumper pin on release of said fiber strand.

12. An actuator for electric stop motion mechanisms for fiber strand draft machines having driven draft rolls, a source of roving supply, a 55 stop motion mechanism and an electro-responsive stop motion release mounted and grounded on said machine comprising a bracket adapted to be mounted and grounded on said machine underneath said fiber strands between said draft

rolls and source of fiber strand supply having transverse slits in an end wall thereof, an insulation block adjacent the split portion of said end wall, means connecting said block to said upper and lower split wall portions, stop motion release electric circuit connecting means projecting from the upper split wall portion, a bumper pin on the end wall and a contact pin on the lower end wall portion vertically offset from said bumper pin and an arm having a corrugated upper surface and the end wall thereof pivotally mounted on said upper end wall portion of said bracket, whereby on breakage of a fiber strand the broken portion moved by said draft rolls may fall on said corrugated surface and tilt said arm 15 from a normal position contacting said bumper pin to a tilted position to contact said contact pin to complete the grounded circuit to actuate said electro-responsive stop motion release. 20

13. An actuator for electric stop motion mechanisms for fiber strand preparation machines having a source of fiber strand supply, driven draft means for said fiber strands, mechanism to stop the motion thereof, electro-responsive means to release said stop motion mechanism and an electric circuit connected to said electro-responsive means, comprising pivotable switch means connected to and normally breaking said circuit pivotally mounted on said machine underneath said fiber strands ahead of said draft 30 means having a rigid roughened upper surface portion adapted to be engaged by a broken strand of fiber and to be pulled thereby through the action of said draft means to pivot said switch means through the pulling action of the fiber strands 35 alone to complete the circuit to actuate said electroresponsive means to release said stop motion mechanism.

14. An actuator for electric stop motion mechanisms for fiber strand preparation machines having a source of fiber strand supply, driven draft rolls for said fiber strands, mechanism to stop the motion thereof, electro-responsive means to release said stop motion mechanism and an electric circuit connected to said electro-responsive means, comprising pivotable switch means connected to and normally breaking said circuit pivotally mounted on said machine underneath said fiber strands ahead of said draft rolls having a rigid roughened movable surface portion adapted to be engaged by a broken strand of fiber and to be pulled thereby through the action of said draft means to pivot said switch means through the pulling action of the fiber strands alone to complete the circuit to actuate said electroresponsive means to release said stop motion mechanism. 40 45 50 55

FREDERICK EXLEY.
